CLAIM

An ornamental design for combined eyeglasses with a stereo headset, as shown and described.

DESCRIPTION

FIG. 1 is a perspective view of the combined eyeglasses with a stereo headset showing our new design;

FIG. 2 is a front view thereof;

FIG. 3 is a side view thereof;

FIG. 4 is a rear view thereof;

FIG. 5 is a top view thereof; and,

FIG. 6 is a bottom view thereof.

FIG. 3 is representative of both side views of the eyeglasses with a stereo headset, as the views are symmetrical.

FIG 1

FIG 2

FIG 3

FIG 4

FIG 5

FIG 6
